UNITED STATES PATENT OFFICE.

MATTHEW T. CHAPMAN, OF AURORA, ILLINOIS.

WELL-SINKING APPARATUS.

1,264,155.

Specification of Letters Patent. Patented Apr. 30, 1918.

Application filed May 18, 1914. Serial No. 839,382.

To all whom it may concern:

Be it known that I, MATTHEW T. CHAPMAN, a citizen of the United States, residing at Aurora, in the county of Kane and State of Illinois, have invented certain new and useful Improvements in Well-Sinking Apparatus, of which the following is a specification, reference being had to the accompanying drawing.

10 This invention relates to well-sinking apparatus, and has for its object the improvement of devices of this type whereby their operation may be made more effective and more rapid. The means by which I have 15 accomplished this object are illustrated in the drawings and are hereinafter specifically described.

In the drawings,—

Figure 1 is a side elevation, partly broken 20 away, of the preferred form of my improved apparatus;

Fig. 2 is a top or plan view of a slightly modified form of apparatus;

Fig. 3 is a longitudinal section taken on 25 line 3—3 of Fig. 2;

Fig. 4 is a top or plan view of the form of apparatus shown in Figs. 2 and 3, but showing it equipped with a different form of operating device;

30 Fig. 5 is a side elevation of the form of device shown in Fig. 4, partly broken away and partly in central vertical section;

Fig. 6 is a side elevation of a part of the equipment to be used in connection with the 35 form of apparatus shown in Fig. 1;

Fig. 7 is a top or plan view of the parts shown in Fig. 6;

Figs. 8 and 9 are detail views showing the wedges used in the constructions of 40 Figs. 4 and 5;

Fig. 9^a is a cross-section on line 9^a—9^a of Fig. 9.

Referring to the drawings,—

Fig. 1 represents the form of device I prefer to use embodying in one complete structure a turntable adapted to be equipped with two separate gripping means by which a boring-pipe can be rotated, both of which separate means can be used at the same time, if desired. Figs. 4 and 5 represent a modified form of turntable equipped with my improved means for holding the boring-pipe against turning when lowering into the well or withdrawing therefrom a long line

of boring-pipes, and also equipped with 55 means for driving a suitable wrench for gripping the upper section of boring-pipe for rotating it. Figs. 2 and 3 represent the same turntable as that shown in Figs. 4 and 5, but showing it equipped with a different 60 type of turning means adapted for use in drilling. Inasmuch as many of the details of the construction illustrated in Fig. 1 are the same as those of the construction illustrated in Figs. 2 to 5, I have not deemed it 65 necessary to illustrate in detail the structure of Fig. 1, which will be readily understood from my description of the same devices in connection with Figs. 2 to 5. I will, therefore, first describe the construction of 70 Figs. 2 to 5, even though the construction of Fig. 1 is the preferred construction.

Referring now to Figs. 2 to 5 and Figs. 8, 9 and 9^a,—25 indicates a framework, of any suitable type, located at the upper end 75 of a well, having mounted thereon a bed-plate 26. Rising from the upper face of the bed-plate 26 is a heavy, circular ring or base 27, upon the upper edge of which is suitably mounted a turntable or rotary 28 80 which comprises a downwardly-extending sleeve 29 inside of the base 27. Annular bearing rings 30 and 31 with anti-friction rollers 33 interposed between them are used between the rotary 28 and the upper edge of 85 the base 27, the ring 31 being in the form of an angle-iron or steel with a vertical flange rising from the outer edge.

As best shown in Fig. 3, the sleeve 29 of the rotary 28 is provided near its lower edge 90 with an annular groove 33 into which a block 34 is adapted to be moved by means of a set-screw 35 mounted in the base 27 at one side thereof. As will be readily understood, the block 34 serves to hold the sleeve 95 29 locked down in position relative to the base 27. If desired, a plurality of such locking devices may be used.

The rotary 28 is provided at each side with upright posts 36 removably mounted 100 in suitable sockets in said rotary, as is ordinary practice in machines of this type. The rotary is also provided on its under face with an annular gear 37 with which meshes a gear 38 fixed upon one end of a shaft 39 105 journaled in a suitable bearing 40 rising from the bed-plate. As will be readily understood, upon the application of power to

the shaft 39 in one direction or the other, the rotary 28 will be rotated in a corresponding direction.

Coming now to the means for turning the boring-pipe for boring purposes,—41 indicates a boring-pipe extending down into the well, having connected to its upper end a boring-bar 42 by means of a screw-threaded coupling 43. As is best shown in Fig. 2, 10 the boring-bar 42, in the construction shown, is square in cross-section, being adapted to slide freely longitudinally of itself in a square collar 44 which has a tapered, square seat in the hub 45 of a plate 46. As shown 15 in Figs. 2 and 3, the plate 46 is seated in the rotary 28 and is rotatable therewith, being held against rotation relative to the rotary by means of a plurality of teeth 47 on the plate engaging suitable notches 48 in the 20 rotary. In the construction shown, the boring-bar 42 is provided with a longitudinal opening therethrough communicating with the interior of the hollow pipe sections 41, whereby a supply of water may be fed 25 through the string of boring-pipes to the drill at its lower end for washing up the borings as the work progresses.

Referring now especially to Figs. 4 and 5,—it will be noted that the plate 46 is removed from the rotary, a plate 49 being substituted, the plate 49 being mounted in the bed-plate 26 or the base 27 and being held against rotation by means of a plurality of teeth 50 engaging suitable notches 51. The plate 49 has rising from it a housing 52 which is cored out conically, as best shown in Fig. 5, for slidably supporting a plurality of slips in the form of wedges 53 about the boring-pipe 41. In the construction shown, four wedges are used, and that is the number I prefer to employ. Each of the wedges 53 is provided with a T-shaped rib 54 adapted to slide freely in a suitable groove in the housing 52, whereby 45 the wedges are moved toward and away from the boring-pipe as they are moved up and down longitudinally of the boring-pipe. As will be appreciated from an inspection of Figs. 4 and 5, the wedges 53 are of two 50 different types, one having teeth extending vertically as shown in Fig. 8, and the other having teeth extending horizontally as shown in Fig. 9, the two types of wedges being arranged alternately about the housing 52. By this arrangement two wedges having vertically-extending teeth are provided diametrically opposite each other adapted to hold the boring-pipe 41 against rotation relative to the housing, and two 55 of the wedges having horizontally-extending teeth are located diametrically opposite each other adapted to hold the boring-pipe against downward movement into the well. As best shown in Fig. 5, 55 indicates a plate 60 bolted to the plate 50 and revolvably sup-

porting a conical shell 56 by means of a hub 57 connected therewith. The shell 56 is provided also with an annular gear 58 meshing with a gear 59 fixed upon a short shaft 60 journaled in the housing 52 at one side 70 thereof. The shaft 60 is provided at its outer end with a socketed head 61 adapted to be rotated or rocked through the medium of a shaft 62 slidably mounted in a suitable bearing in the base 27 and in a standard 75 63 rising from the bed-plate 26. The shaft 62 is provided at its outer end with a turning-device 64 of any approved type, by which the shafts 62 and 60 can be rotated for turning the gears 58 and the shell 56 80 on a vertical axis about the boring-pipe 41. As is best shown in Fig. 9^a, the wedges 53 are provided with outwardly-projecting pins 65, shown diagrammatically in Fig. 5 as working in diagonally-positioned slots 66 85 in the shell 56, whereby said wedges are raised and lowered by an appropriate turning of the said shell.

The wrench used for turning the upper end of two united sections of boring-pipe in 90 connection with the holding means shown in Fig. 5, comprises two handles 67—68 (see Figs. 10 and 11) adapted to be engaged by the upright posts 36 of the rotary for turning purposes. The construction of the 95 wrench is such that it is adapted to bind tightly upon the boring-pipe for causing the pipe to rotate with the rotary.

With the turntable 28 provided with the plate 46, as shown in Fig. 3, and with the 100 boring-pipe 42 connected by means of a coupling 43 with the boring-pipe 41, upon the application of power to the shaft 39 the boring-pipe will be rotated for boring purposes, as will be readily understood, the engagement of the boring-pipe 42 with the rotary 28 being such that the boring-pipe 41 can rise and fall freely relative to the rotary. When boring has progressed so as to bring the upper end of the boring-bar approximately to the plate 46 of the rotary, the boring-bar will be disconnected from the boring-pipe 41 and another section of boring-pipe will be interposed between the boring bar and the line of connected sections of boring-pipe. Whenever in the use of the devices heretofore described it is desired to remove the whole line of boring-pipe sections from the well, the plate 46 is removed and the plate 49 is placed in position as 110 shown in Figs. 4 and 5, the boring-bar 42 being also laid aside for the time being. The line of boring-pipe sections is then raised by means of hoisting means (not shown) to bring one of the couplings 43 between two sections of the boring-pipe into the position shown in Fig. 5. The weight of the wedges 53 is such that they automatically settle into gripping position to hold the section of pipe both against longitudinal 115 120 125 130

movement and against rotation. By the use of a wrench placed in position upon the section above the coupling 43 the upper section of boring-pipe is unscrewed from the lower section and laid aside for future use. The line of boring-pipe sections is then raised by means of any suitable means to bring another of the couplings 43 into the position shown in Fig. 5, the wedges 53 being adapted to give upward to permit the passage of the coupling, whereupon the operation as just described is repeated. For placing the line of boring-pipes in the well, the operation is substantially the reverse of that just described, the rotary being driven in the opposite direction with the wrench inverted so as to turn the successive upper sections for screwing the sections together instead of for unscrewing them. In order to move the wedges 53 apart to permit the passage of the couplings 43 downward between the wedges, the turning-device 64 is to be rotated, as will be readily understood, turning the shell 56 and forcing the wedges upward and outward. Upon the passage of one or more couplings 43, as desired, the turning-device 64 is released to permit the wedges 53 to settle into gripping position, as will be readily understood. Upon the completion of the installation of the boring-pipes in position, the plate 49 will be removed and the plate 46 and the boring-bar 42 will be placed in position ready for the work of boring to proceed.

Coming now to Figs. 1, 6, and 7, which show the preferred form of construction, the corresponding parts are indicated by the same reference characters but with the addition of an exponent "a". In this construction, the rotary 28 is dispensed with a rotary 74 being substituted therefor having a considerably greater vertical height than the rotary 28 so as to bring the upper closure-plate of the rotary sufficiently above the bed-plate that the plate 49 and the parts carried thereby can be retained in position during the boring operation. In the form shown in Fig. 1 a top closure-plate 75 is used in place of the plate 46 of the construction first described, being held in position in the same manner but differing from the plate 46 in that it is provided with a considerably larger square opening 76 at its center. A plate 77 (see Figs. 6 and 7) having a working fit in the square opening 76 of the plate 75 is substituted for the collar 44 of the construction first described, the plate 77 being provided with a collar or hub 78 corresponding in a general way to the collar 44 and adapted to work with the boring-bar in precisely the same manner. The wrench illustrated in Fig. 1 also differs slightly from that shown in Fig. 5, but the operation is, generally speaking, the same.

Inasmuch as the operation of the device of

Fig. 1 is the same as that of the device of Figs. 2 to 5, except that it is not necessary to remove the plate 49^a when the device is to be used for boring purposes or to remove the plate 75 when the device is to be used for withdrawing or replacing a line of boring pipes, it is believed that it is unnecessary to further describe the operation herein.

While I have shown in my drawings a construction employing two pairs of oppositely-disposed coöperating wedges, it will be understood that I do not wish to limit myself to that construction except as hereinafter specifically claimed. Such a construction comprises a wedge (either of the two wedges) provided with suitable coöperating means (the other wedge) for accomplishing the desired result. It will be understood that I do not wish to claim a second wedge as the "coöperating means" except as particularly specified.

That which I claim as my invention, and desire to secure by Letters Patent, is,—

1. In a well-sinking apparatus, the combination of a base in the form of an upwardly-extending ring, a rotary mounted thereon comprising a sleeve extending down inside of said ring, means at one side of said base engaging said rotary for driving it, and a block mounted in said base and working in a groove in said sleeve for locking said rotary in position upon said base.

2. In a well-sinking apparatus, the combination of a base in the form of an upwardly-extending ring, a rotary mounted thereon comprising a sleeve extending down inside of said ring, means at one side of said base engaging said rotary for driving it, a block mounted in said base and working in a groove in said sleeve for locking said rotary in position upon said base, and adjustable means for moving said block into and out of operative engagement with said groove.

3. In a well-sinking apparatus, the combination of a base, a rotary revolvably mounted thereon, means for driving said rotary, a plate removably mounted in said base, means carried by said plate for holding a section of boring-pipe against rotation, a second plate removably mounted in said rotary, and means carried by said second plate for holding another section of boring-pipe against rotation relative to said rotary.

4. In a well-sinking apparatus, the combination of a base, a rotary revolvably mounted thereon, means for driving said rotary, a plate removably mounted in said base at its lower end, means carried by said plate for holding a section of boring-pipe against rotation, a second plate removably mounted in the upper end of said rotary, and means carried by said plate for holding another section of boring-pipe against rotation relative to the rotary.

5. In a well-sinking apparatus, the combi-

nation of a base, a rotary revolubly mounted thereon, means for driving said rotary, means carried around by the rotary for rotating a section of boring-pipe, a gripping-block, stationary supporting means having a diagonally-positioned slideway for said gripping-block whereby said block is movable diagonally down and up toward and away from said boring-pipe, a shell 5 revolubly mounted about said gripping-block, means for rotating said shell, means operated by the rotation of said shell for raising said gripping-block out of contact with said boring-pipe, and means co-operating with said gripping-block for holding said boring pipe against downward movement.

6. In a well-sinking apparatus, the combination of a base, a rotary revolubly mounted thereon, means for driving said rotary, means carried around by the rotary for rotating a section of boring-pipe, gripping-blocks, stationary supporting means having diagonally-positioned slideways for said gripping-blocks, a shell revolubly mounted about said gripping-blocks, means for rotating said shell, and pins mounted on said gripping-blocks engaging diagonally-positioned slots in said shell whereby the rotation of said shell serves to raise said gripping-blocks out of contact with said boring-pipe.

7. In a well-sinking apparatus, the combination of a base, a rotary revolubly mounted thereon, means for driving said rotary, means carried around by the rotary for rotating a section of boring-pipe, a housing removably mounted on said base and provided with diagonally-positioned slideways, and 35 downwardly-tapering wedges mounted in said housing and slideable up and down in said slideways.

8. In a well-sinking apparatus, the combination of a base, a rotary revolubly mounted thereon, means for driving said rotary, means carried around by the rotary for rotating a section of boring-pipe, a housing mounted on said base, a plurality of downwardly-tapered wedges supported within said 45 housing and adapted to settle into locking engagement with a boring-pipe extending through the housing, a shell revolubly mounted about the lower ends of said wedges, means for rotating said shell, and pins mounted on said wedges working in diagonally-positioned slots in said shell whereby a partial rotation of said shell serves to lift said wedges out of contact with said boring-pipe.

60 9. In a well-sinking apparatus, the combination of a base, a rotary revolubly mounted thereon, means for driving said rotary, means carried around by the rotary for rotating a section of boring-pipe, a housing

mounted on said base, a plurality of downwardly-tapered wedges supported by said housing and adapted to settle into locking engagement with a boring-pipe extending through the housing, a shell revolubly mounted about the lower ends of said wedges, an annular gear mounted upon said shell, pins carried by said wedges working in diagonally-positioned slots in said shell whereby a partial rotation of said shell serves to raise said wedges out of contact with said boring-pipe, a second gear meshing with said first-mentioned gear, a shaft upon which said second gear is mounted, and means removably connected with said shaft for rotating the same.

10. In a well-sinking apparatus, the combination of a base, a rotary revolubly mounted thereon, means for driving said rotary, means carried around by the rotary for rotating a section of boring-pipe, and gripping means mounted in diagonally-positioned slide ways on said base adapted to automatically grip said pipe for supporting the pipe and holding it against rotation.

20 11. In a well-sinking apparatus, the combination of a base, a rotary revolubly mounted thereon, means for driving said rotary, means carried around by the rotary for rotating a section of boring-pipe, a housing supported from said base provided with diagonally-positioned slide ways, and gripping means mounted in said slide ways adapted to automatically grip said pipe for supporting the pipe and holding it against rotation.

30 12. In a well sinking apparatus, the combination of a base, a rotary revolubly mounted on said base, means for driving said rotary, means carried around by the rotary for rotating a section of pipe, a plurality of wedges each having a T-shaped rib on its outer face, and a stationary housing supported from said base having diagonally-positioned slideways for said ribs and providing a conical seat within which said wedges are held slidably in contact with said pipe for holding the pipe against downward movement.

40 13. In a well sinking apparatus, the combination of a base, a rotary revolubly mounted thereon, means for driving said rotary, means carried around by the rotary for rotating a section of boring pipe, a ring having a downwardly tapering opening non-revolubly mounted within the rotary, and wedges in said ring adapted to engage a section of the boring pipe extending through said rotary.

50 14. In a well sinking apparatus, the combination of a base, a rotary revolubly mounted thereon, means for driving said rotary, means carried around by the rotary for rotating a section of boring pipe, a ring having a downwardly tapering opening

- non-revolubly mounted within the rotary, 65
wedges in said ring adapted to engage a
section of the boring pipe extending
through said base, and a stationary means
5 for moving said wedges into and out of
contact with said boring pipe whereby said
boring pipe may be held against movement
relative to said ring.
15. In a well sinking apparatus, the com- 10
bination of a base, a rotary revolubly
mounted thereon, means for driving said
rotary, means carried around by the rotary
for rotating a section of boring pipe, a funnel-shaped ring non-rotatably mounted upon
15 said base, wedges slidably mounted in said
ring adapted to move inward into contact
with said pipe as they move downward in
said ring, means serving to move said
wedges outward out of contact with said
20 pipe as they are moved upward, and means
for moving said wedges upward or down-
ward in unison.
16. In a rotary well sinking apparatus, 25
the combination of a base, a rotary revolubly
mounted thereon, means for driving said
rotary, means carried around by the rotary
for rotating a section of boring pipe ex- 30
tending vertically through said base and
said rotary, a funnel-shaped ring non-rotat-
ably mounted upon said base about said
pipe, wedges slidably fitted in the hollow
ring adapted to engage said pipe for hold-
35 ing it against downward movement and
against rotation, and means for moving said
wedges in unison either upward and out-
ward or downward and inward.
17. In a rotary well sinking apparatus, 40
the combination of a base, a rotary revolubly
mounted thereon, means for driving
said rotary, means carried around by the
rotary for rotating a section of boring pipe
extending vertically through said base and
45 said rotary, a funnel-shaped ring non-rotat-
ably mounted upon said base about said
pipe, wedges slidably fitted in the hollow
ring adapted to engage said pipe for hold-
ing it against downward movement and
50 against rotation, and rotary means for mov-
ing said wedges in unison either upward
or downward in said ring serving to move
the wedges outward as they rise and to
move them inward as they descend.
18. In a rotary well sinking apparatus, 55
the combination of a base, a rotary revolubly
mounted thereon, means for driving said
rotary, means carried around by the rotary
for rotating a section of boring pipe exten-
ding vertically through said base and said
60 rotary, a funnel-shaped ring non-rotatably
mounted upon said base about said pipe,
wedges slidably fitted in the hollow ring
adapted to engage said pipe for holding it
against downward movement and against
65 rotation, and means revolubly mounted
about said wedges having diagonally-posi- 70
tioned slots which engage said wedges
whereby upon the rotation of said means
in one direction said wedges are moved up-
ward in unison out of engagement with the
75 pipe and upon rotation in the opposite di-
rection said wedges are moved downward
in unison into engagement with said pipe.
19. In a rotary well sinking apparatus, 80
the combination of a base, a rotary revolubly
mounted on said base, means for driv- 85
ing said rotary, means carried around by
the rotary for rotating a section of boring-
pipe extending vertically through said base
and said rotary, a funnel-shaped housing
non-rotatably mounted upon said base
about said pipe, wedges slidably mounted
in the hollow housing adapted to be moved
downward and inward into engagement
with said pipe or upward and outward out
of engagement, rotary means by the rota-
tion of which said wedges are moved up and
down in said housing, and a shaft mounted
on said base and removably connected with
said rotary wedge-moving means for driv- 90
ing the same.
20. In a rotary well sinking apparatus, 95
the combination of a base, a rotary revolubly
mounted on said base, means for driv-
ing said rotary, means carried around by the
rotary for rotating a section of boring pipe
extending vertically through said base and
100 said rotary, a funnel-shaped housing non-
rotatably mounted upon said base about said
pipe, wedges slidably mounted in the hollow
housing adapted to be moved downward and
inward into engagement with said pipe or
105 upward and outward out of engagement, a
rotary member for moving said wedges up
and down in unison, a short shaft mounted on
said base, and gearing between said shaft and
said rotary member for rotating said mem-
ber through the medium of said shaft.
21. In a rotary well sinking apparatus, 110
the combination of a base, a rotary revolubly
mounted on said base, means for driv-
ing said rotary, means carried around by the
rotary for rotating a section of boring pipe
extending vertically through said base and
115 said rotary, a funnel-shaped housing non-
rotatably mounted upon said base about said
pipe, wedges slidably mounted in the hollow
housing adapted to be moved downward and
inward into engagement with said pipe or
120 upward and outward out of engagement,
a rotary member for moving said wedges up
and down in unison, a short shaft mounted on
said base, gearing between said shaft and
said rotary member for rotating said mem-
ber through the medium of said shaft, and a
second shaft slidably mounted on said
base and detachably connected with said
first-named shaft.
22. In a rotary well sinking apparatus, the

- combination of a base, a rotary revolvably mounted on said base, means for driving said rotary, means carried around by the rotary for rotating a section of boring-pipe 5 extending vertically through said base and said rotary, a funnel-shaped housing non-rotatably mounted upon said base about said pipe, wedges slidably mounted in the hollow housing adapted to be moved downward and 10 inward into engagement with said pipe or upward and outward out of engagement, a rotary shell surrounding the lower ends of said wedges within said housing and adapted by its rotation to move said wedges up and 15 down in unison, gearing connected with said shell for rotating it, and a short shaft mounted on said base and detachably connected with said gearing for operating the same.
- 20 23. In improvements of the character disclosed, the combination, with a rotary table, a boring string, and means for connecting said table with said boring string for rotating it; of means for supporting the string 25 adapted to engage the same at any point of its length and to so support the string independently of the table; said table being provided with a base upon which the table is rotatively supported; said means for supporting the string being applied to the string and to said base; said string-supporting means consisting of slips.
24. In a well sinking apparatus, the combination of a base, a rotary revolvably mounted 30 on said base, means for driving said rotary, means carried around by the rotary for rotating an upper section of boring pipe, a wedge, and means non-rotatably mounted 35
- relative to said base adapted to coöperate with said wedge for holding a lower section 40 of boring pipe against rotation.
25. In a well sinking apparatus, the combination of a base, a rotary revolvably mounted on said base, means for driving said rotary, means carried around by the rotary 45 for rotating an upper section of boring pipe, means mounted within said rotary and held against rotation relative to the base, and wedges supported by said non-rotatable means adapted to engage a lower section of 50 boring pipe for holding said pipe against rotation and against downward movement.
26. In a well sinking apparatus, the combination of means for holding a section of boring pipe against turning, comprising a support and a wedge-shaped gripping block 55 slidably mounted in said support adapted upon an upward movement to move laterally away from said pipe, and a cam device for raising said block out of operative engagement with the pipe.
27. In a well sinking apparatus, the combination of means for turning an upper section of boring pipe, and means for holding a lower section of said pipe against turning, comprising a wedge-shaped gripping block 60 having an angular seat whereby upon an upward movement said block is carried away from said pipe, a cam device engaging said gripping device, and means for operating said cam for moving the gripping block out of operative engagement with the pipe.

MATTHEW T. CHAPMAN.
